UNITED STATES PATENT OFFICE.

LAURA K. LITCHFIELD, OF NEW YORK, N. Y.

GARMENT.

1,229,986.

specification of Letters Patent. Patented June 12, 1917.

Application filed July 18, 1916. Serial No. 110,072.

To all whom it may concern:

Be it known that I, LAURA K. LITCHFIELD, a citizen of the United States, and a resident of the city of New York, borough 5 of Manhattan, in the county and State of New York, have invented a new and Improved Garment, of which the following is a full, clear, and exact description.

Among the principal objects which the 10 present invention has in view are: to provide a one-piece garment arranged to produce the effect of a skirt and bloomers; to provide a garment of the character mentioned adapted to permit ease and freedom 15 of the legs of the wearer; to provide a one-piece skirt garment closed at the bottom; to provide a bloomer-like garment having a skirt portion; and to provide a bathing garment of the character mentioned, the bottom portion of the skirt whereof cannot be 20 lifted to remain on or above the hips of the wearer.

Drawings.

Figure 1 is a pictorial view showing a garment constructed and arranged in accordance with the present invention as being worn as a bathing suit, the skirt being shown as falling to its natural position;

Fig. 2 is a similar view showing the skirt 30 as being lifted;

Fig. 3 is a view of the garment showing the under side thereof, the skirt being extended to show the bloomer and crotch effect;

Fig. 4 is a view showing the garment as worn, the skirt being lifted to an extreme position to show the method of shaping the seat and crotch;

Fig. 5 is a view showing the cross section of the garment;

Fig. 6 is a section taken as on the line 6—6 in Fig. 5.

Description.

As seen in the drawings, the garment has a bodice portion 11, which is provided with a belt 12 and is integrally connected with a bloomer portion 13. It will be understood, however, that the bodice portion 11 50 may be of different designs and styles. The bloomer portion 13 is gathered at the bottom and provided with leg openings 14, the material between which openings is cut and seamed to form a baggy seat portion 15 and a short inside leg portion. The crotch portion is formed by shaping the seat 15 and

the leg-forming portions 16 so that the crotch seam 17 is drawn slightly between the points 18 and 19 where the leg portions are connected with the seat portion 15 and the front of the bloomer portion.

Between the waist line and leg openings of the garment, a short skirt section 20 is provided. Preferably the section 20 is integral with the bloomer portion 13. The section 20 is formed of two thicknesses, the outer thickness being integral with the upper portion of the bloomer portion 13. The outer edges of the two thicknesses are sewed. A line of stitching 21 is then formed 70 securing the top of what is termed the skirt section 20.

The garment is furnished with the usual and desired fittings, such as pockets, belt, lapels and collar. If it is desired, some form 75 of closure member, such as elastic, may be provided for contracting the leg openings.

When the garment is employed as a bathing suit, it is evident that a modish but modest garment is provided. Also it is 80 obvious that the desired freedom of action is permitted to the wearer. When in bathing, a further advantage to the wearer of a suit constructed in accordance with the present invention, is that the waves cannot 85 lift the skirt above the hips, an objection to be found in garments of the usual construction.

While the garment has been herein described in its use as a bathing garment, it 90 will also be understood as being desirable as a garment for women when exercising in a gymnasium or in other athletic pursuits.

A further employment of garments constructed as herein disclosed may be as jumpers or rompers for children. When the garment is employed in this capacity, provision is made for opening and closing the seam 17, and otherwise obviously modifying the formation of what has been styled the seat 100 and crotch portions.

Claims.

1. A garment comprising a skirt embodying a lower portion formed of two thicknesses of fabric, a short bloomer section integral with the under layer of said lower portion, said bloomer section having leg openings, and means for forming a short crotch in said bloomer section between said 110 leg openings.

2. A garment as characterized comprising

a skirt portion; a bloomer portion, said bloomer portion conforming in shape to and forming a lining for the lower section of said skirt portion, said bloomer portion having leg openings formed therein in spaced relation, said openings being formed in the area within the attachment of the bloomer portion and skirt portion.

3. A garment as characterized having a skirt portion; a bloomer portion, said bloomer portion being in part shaped to

conform with and to form a lining for the lower section of said skirt portion, said bloomer portion having leg openings formed therein; and means for permanently attaching the bloomer portion and skirt portion at a point sufficiently high on said skirt portion to prevent the unsupported part of said bloomer portion extending below the lower edge of said skirt portion.
